UNITED STATES PATENT OFFICE.

EVANDER B. McGILVARY, OF MADISON, WISCONSIN.

ATTACHMENT FOR TYPE-WRITERS.

972,776.

Specification of Letters Patent. Patented Oct. 11, 1910.

Application filed September 22, 1905. Serial No. 279,573.

To all whom it may concern:

Be it known that I, EVANDER B. McGILVARY, of Madison, in the county of Dane and State of Wisconsin, have invented a 5 certain new and useful Attachment for Type-Writers, of which the following is a specification.

My invention has for its object the production of an attachment for type-writing 10 machines, whereby at the will of the operator, an auxiliary character, as an under-scoring character, may be printed in predetermined position as the regular characters are formed, thus obviating manipulation of 15 the machine for effecting the insertion or interlineation of the auxiliary character; and to this end, my invention consists in the novel combinations and constructions hereinafter set forth and pointed out in the 20 claims.

In describing this invention, reference is had to the accompanying drawing in which like characters designate corresponding parts in all the views.

Figure 1 is a top plan view, partly broken away, of a type-writing machine embodying one exemplification of my invention, a type-carrying member being shown in printing position. Fig. 2 is an enlarged plan of 25 parts shown in Fig. 1, a portion of a type-carrying member being illustrated in its position assumed when the upper-case type-character thereof is at the printing point, and parts being shown in their inoperative 30 position by dotted lines. Fig. 3 is an elevation of the parts seen in Fig. 2.

In the accompanying drawing I have illustrated the well known "Remington" 35 type of machine, but I do not restrict my invention to use on any particular machine, since the structure can readily be modified for adjustment or attachment to other types of machines, as will be obvious to those skilled in the art.

The device embodying my invention may be constructed as a separate means for subsequent attachment to type-writing machines, or if desired, it may be manufactured and assembled with the machine and form 45 an integral or inseparable part thereof.

1 is the frame of the machine, 2 the platen; and 3, 3 the type-carrying members of the printing instrumentalities. The members 3 are movable singly in converging 50 paths to a common printing position and

are each formed with upper and lower-case characters. 4 is a movable element of the means for determining whether the upper-case or lower-case type-characters will be brought into printing position. This element 4 consists of a bar which extends from side to side of the machine, is movable rearwardly and forwardly, and is suitably connected to a shifting mechanism and to the platen 2, the latter being movable rearwardly and forwardly with the member 4. In the illustrated exemplification of my invention, the member 4 is normally in its forward position so that the lower-case characters are brought into printing position, 65 and upon the operation of the shifting mechanism the member 4 and the platen 2 are moved rearwardly to bring the upper-case characters into printing position. All of the foregoing parts may be of any desirable form, size and construction. 70

As is well known to those skilled in the art, the bringing of upper-case or lower-case characters into printing position although often controlled by shifting the platen, is sometimes determined by shifting the type-carrying members, and therefore I do not restrict my invention to use upon a machine of the illustrated type in which the printing point is shiftable relatively to 80 said characters. Neither do I restrict my invention to a machine having both upper and lower-case characters. 85

5 is the auxiliary-character-carrying member, the illustrated construction thereof consisting of an arm pivoted at 6 at one end and provided with an auxiliary character 7 at its free end, this arm consisting of two sections, the one carrying the character 7, 90 being adjustable relatively to the other section and secured thereto by suitable fastening means 8. The character 7 here shown is supported near the point of convergence of the paths of the printing members 3 and serves to print underscoring in connection 95 with the regular type-characters and in the same letter-spaces, but it will be obvious that said character may be of any desirable form to print any other auxiliary impression. The member 5 is formed with an opening 9 100 which receives the type-characters on the members 3, and is also formed with a contact-surface 10 for receiving the actuating impulses of said members 3.

When my invention is used with machines 110

having their type-bars provided with upper-case and lower-case type-characters, the member 5 is formed with a plurality of openings 9 and contact-surfaces 10, one in 5 advance of the other, the rear opening 9 receiving the lower-case characters and the rear contact-surface 10, Fig. 1, being engaged by the members 3 when assuming printing position, and the front and rear 10 openings 9 receiving, respectively, the lower and upper-case characters, and the front contact-surface 10 being engaged by the members 3; Figs. 2 and 3, when the machine is used for upper-case work. Upon the 15 movement of a member 3 to printing position, the auxiliary-character-carrying member 5 yields or moves upwardly, and upon the return of said member 3, the member 5 returns to its normal position in engagement 20 with any suitable abutment as an arm 11 carried by the frame of the machine and serving to prevent further movement of the member 5 with the type-carrying member, which continues its movement relatively to 25 the member 3.

In the illustrated exemplification of my invention, the member 5 is mounted on a movable support or arm 12 connected by a 30 pivot 13 to a part or block 14 provided on the movable element 4, the pivot 13 being arranged at an angle to the pivot 6. The front end of the support or arm 12 is provided with a handle 15 which facilitates 35 rocking of said support or arm on the pivot 13 to move the auxiliary-character-carrying member 5 into and out of the path of movement of the type-carrying members. A suitable stop, as a screw 16, is carried by the part or block 14 for limiting the movement 40 of the support or arm 12 toward its inoperative or normal position, and the support or arm 12 is provided with an adjustable stop, as a screw 17, for engaging the part or block 14 and limiting the movement of said 45 support or arm in the other direction.

Although the described means for supporting and moving the auxiliary type-carrying member 5 is particularly simple and is readily attached in position, it will be apparent that the same is only one of the many structures suitable for such purpose, and consequently I do not restrict my invention thereto.

Having thus fully described my invention, 55 what I claim as new and desire to secure by Letters Patent, is:—

1. In a type-writing machine, a plurality of type-carrying members movable in converging paths to a common printing point; 60 an auxiliary-character-carrying member located near the point of convergence of said paths and adapted to be operated by the movement of any of said type-carrying members toward its printing position and means for moving the auxiliary-character-

carrying member into and out of the paths of movement of the type-carrying members.

2. In a type-writing machine, the combination of printing instrumentalities, and means, operatively relatable thereto at the 70 will of the operator, for underscoring the printed characters as they are formed.

3. In a type-writing machine, an auxiliary-character-carrying member common to all the type-carrying members and provided 75 with a type-receiving opening; and means for moving said auxiliary-character-carrying member into and out of the path of movement of the type-carrying members and thereby moving said opening into and out of 80 the type-receiving position.

4. In a type-writing machine, a yielding arm carrying an auxiliary character common to the type characters of the machine, a 85 said arm being provided with a type-receiving opening and means for actuating said arm to move said opening into and out of the type-receiving position.

5. In a type-writing machine, the combination of a movable arm, a yielding auxiliary-character-carrying member supported 90 by said arm, and formed with type-receiving aperture and a handle secured to said arm for moving said aperture toward and from its type-receiving position.

6. In a type-writing machine the combination of a movable arm, a yielding auxiliary-character-carrying member supported by said arm and having a contact-surface adapted to receive the actuating impulse of 100 any type-carrying member and means for moving the auxiliary-character-carrying member into operative relation with the type-carrying member whereby a type character and the auxiliary character are printed 105 simultaneously.

7. In a type-writing machine, the combination, with type-carrying members movable singly in converging paths to a common printing position, of an auxiliary-character-carrying member actuated by any one of the type-carrying members during the movement of the latter toward its printing position.

8. In a type-writing machine, the combination with a plurality of type and type-carrying members having a common printing position, means for moving them singly toward and from said position, and means actuated by the movement of any one of the 115 type-carrying members toward said printing position for printing an auxiliary character as a type character is printed.

9. In a type-writing machine, the combination with printing instrumentalities 125 adapted to print the type characters singly, of means for printing an auxiliary character simultaneously therewith and in the same letter-space.

10. In a type-writing machine, the combi- 130

nation of printing instrumentalities and means for underscoring a printed character simultaneously with the printing thereof.

11. In a type-writing machine, a movable member carrying an auxiliary character common to the upper-case and the lower-case type-characters of the type-carrying members, means for moving an upper or lower-case character to the printing position, and means for moving the first-mentioned member into the path of movement of the type-carrying members.

12. In a type-writing machine, upwardly striking type-carrying members movable in converging paths to a common printing position, a pivoted member carrying an auxiliary character, and means for moving said pivoted member relatively to the type-carrying members to bring the auxiliary character into a predetermined position near the point of convergence of said paths.

13. In a type-writing machine, type-carrying members, and a member carrying an auxiliary character and pivoted on axes arranged at an angle to each other, said member being movable on an axis into printing position and being movable on another axis relatively to the type-carrying members.

14. In a type-writing machine, type-carrying members, an arm pivoted at one end and carrying an auxiliary character at its other end, means for moving said arm relatively to the type-carrying members to bring the auxiliary character into a predetermined position said arm including means for adjusting the auxiliary character relatively to the first-mentioned means.

15. In a type-writing machine, type-carrying members, a movable member carrying an auxiliary character, said member comprising two sections, one being provided with the auxiliary character and adjustable relatively to the other section, and means for moving said member relatively to the type-carrying members to bring the auxiliary character into a predetermined position.

16. In a type-writing machine, the combination of a type-carrying member, and an auxiliary-character-carrying member movable with the type-carrying member and having an aperture for receiving the type of the first-mentioned member, said type-carrying member being movable from printing

position relatively to the auxiliary-character-carrying member.

17. In a type-writing machine, the combination of printing instrumentalities including upper-case and lower-case type-characters, and a movable member carrying an auxiliary character common to said upper-case and lower-case type-characters.

18. In a type-writing machine, type-carrying members including upper-case and lower-case type-characters, a movable member carrying an auxiliary character and movable by the type-carrying members, and means for moving said member relatively to the type-carrying members into position to print with the upper-case or lower-case type-characters.

19. In a type-writing machine, printing instrumentalities including upper-case and lower-case type-characters, means for shifting the platen to effect the registration of the upper-case or lower-case type-characters in printing position, and an auxiliary-character-carrying member movable with said means.

20. In a type-writing machine, printing instrumentalities including upper-case and lower-case type-characters, means for shifting the platen to effect registration of the upper-case or lower-case type-characters in printing position, said means including a movable element connected to the platen, and an auxiliary-character-carrying member mounted on said movable element and movable therewith, the last-mentioned member being movable relatively to said movable element.

21. In a type-writing machine, type-carrying members, and a movable member carrying an auxiliary character and provided with type-receiving openings arranged one in advance of the other and with contact-surfaces arranged one in advance of the other.

In testimony whereof, I have hereunto signed my name in the presence of two attesting witnesses, at Madison, in the county of Dane, in the State of Wisconsin, this 18th day of September, 1905.
